UNITED STATES PATENT OFFICE.

DEVEREUX JOHN GREGORY WATKINS, OF LINCOLN, ENGLAND.

WINDPROOF LAMP.

Application filed July 26, 1927, Serial No. 208,527, and in Great Britain August 31, 1926.

This invention comprises improvements in or relating to wind proof lamps and has among its objects to provide an oil lamp which will burn clearly and evenly and with 5 almost complete immunity from flare in any wind, will provide a constantly good light for exceptionally long periods without necessitating the trimming of the wick or attention other than maintaining the supply 10 of oil, and will burn without smoking and consequently without depositing soot upon the lamp top or other parts.

These objects are attained by so constructing the lamp as to obtain a scientific balancing of air currents circulating within the lamp and without the employment of baffle plates or gauzes which in a wind or draught necessitate a comparatively small flame or the use of a lamp chamber or casing which 20 is large in comparison with the size of the flame.

According to the present invention a lamp is provided embodying an outer cylinder closed at its base or lower part and having 25 concentric therewith at its upper part a plurality or series of open based inner cylinders of proportionately decreasing diameters and lengths, said inner cylinders having outwardly projecting top flanges spaced one 30 above another, and the arrangement, disposition and relative dimensions of said cylinders and flanges being such as to provide within the lamp a space in which a flame will burn undisturbed by any outside air currents 35 or climatic conditions yet producing its own convective currents which have both ingress and egress at the top of the lamp.

For the purpose of more fully describing the nature of this invention reference will 40 now be made to the accompanying drawings, wherein:—

Figure 1 illustrates in part sectional elevation a lamp constructed in accordance with this invention, the upwardly converging 45 broken lines indicating graphically the proportionately decreasing depths and diameters of the cylinders.

Figures 2, 3, 4 and 5 illustrate in vertical section modified constructions hereinafter 50 described.

In one method of carrying out the invention the lamp is provided with an outer cylinder 1 of glass or the like or of any suitable material having one or more windows of glass 55 or equivalent transparent material, said cylinder being closed at its base, advantageously

by a member 2 which constitutes an oil vessel and has the burner 3 projecting up therefrom. This cylinder is open at the top and has an outstanding horizontal flange 1^a.

Concentrically disposed within the upper part of the outer cylinder 1 are a plurality of further cylinders 4, 5, having outwardly projecting flanges 4^a, 5^a, respectively by which said cylinders are supported in position. 60 The several cylinders are spaced apart radially so as to form annular passages 6, 7, and the top of the innermost cylinder 5 is closed. Also, the several flanges 1^a, 4^a and 5^a are suitably spaced by means such as adjustable 65 screw members 8, the spaces opening out at the periphery of the flanges forming continuations of the annular passages 6, 7.

It has been found by experiment that by providing concentric cylinders of definite 70 relative dimensions proportionately decreasing both diametrically and vertically from the outer to the innermost cylinder, and also by mounting said cylinders so as to form the annular passages 6, 7 between 75 same of proportionally decreasing size inwardly and the openings 9, 10 at the flange peripheries of proportionally decreasing sizes, a flame space is provided, the air within which space is undisturbed by 80 exterior air currents and atmospheric conditions. Additionally it is found that the flame will choose for its own convective currents the outer passages such as 6 and 9 as 85 inlets and the inner passages such as 7 and 10 as outlets.

To produce the desired results, the following proportional sizes of the several parts and passages have been found effective. The outer cylinder or casing 1 may be of any reasonable size but having a height greater than the diameter, the flange 1^a being formed of metal or any other suitable material and secured in any desired manner. The cylinders 4 and 5 are of simple descending proportion, i. e. the diameter of the outer cylinder being 95 to the second cylinder 4 as the latter is to the third cylinder 5, and the lengths or heights of the inner cylinders 4, 5 are equal to their respective diameters. The flanges 1^a, 4^a and 100 5^a are spaced apart to an amount equal to the annular spaces 6 and 7 between the respective cylinders.

To complete the efficiency of the arrangement the peripheral openings 9, 10 should be 105 so contracted that the total circumferential area of each opening should equal the circum-

ferential area of the annular passage with which the same communicates, i. e. the circumferential area of opening 9 should equal that of passage 6, and the area of opening 10 that of passage 7. In other words, the width of a required external opening multiplied by the circumference of the flanges must equal the difference in superficial area of the two cylinders bounding the annular passage communicating with said opening.

So long as the inlet and outlet openings 9 and 10 are kept in correct relative proportion it is possible and sometimes advisable proportionately to reduce or increase same, and to this end said openings may be adjustable.

It will be appreciated that the number of concentric cylinders employed may be varied as desired, but for the majority of purposes and excepting when constructing comparatively large lamps, the provision of two or three inner cylinders is sufficient.

The burner is preferably so positioned that the flame of the lamp is located at or below a horizontal line in the main cylinder or casing 1 at a position where the depth of said cylinder equals its diameter. The flame can, if desired, be unprotected, but owing to the extreme fluidity of air and to the difficulty in obtaining absolutely accurate construction, the central cone of air may have occasional movement and cause small lateral movements of the flame, and in order to obviate this and ensure an absolutely steady flame, a small glass or like chimney or tube 11 is preferably assembled around the flame so as to project up into said air cone.

The contracted inlet and outlet openings 9 and 10 may be produced in a variety of ways. In Figure 1, the flanges 4^a and 5^a are formed with depending peripheral rims 4^b and 5^b.

In Figure 2 the flanges 4^a and 5^a are inclined downwardly to their peripheries, the inclination of 4^a being less than that of 5^a.

In Figure 3 the lower or main cylinder flange 1^a has a small upturned rim 1^b, the upper flange 5^a has a depending rim 5^b and the intermediate flange 4^a has a rim 4^c which projects both upwardly and downwardly therefrom.

In Figure 4 the lower flange 1^a slopes upwardly and the upper flange 5^a downwardly towards their peripheries, while the intermediate flange 4^a is a dual member formed of two plates inclining in a divergent manner outwardly.

In Figure 5 each of the several flanges comprises a flat disc, the area of the openings at the circumference of said discs being contracted to the required relative sizes by gauze or like perforated material 12 of calculated mesh.

In a further construction three parallelly spaced flanges 1^a, 4^a and 5^a are provided and

around the periphery of the central flange 4^a is fixed or formed a plain circular strip of proper calculated width so placed as to provide openings 9 and 10 of the exact required sizes.

In a lamp constructed in accordance with this invention, the lamp top composed of spaced discs is maintained comparatively cool by reason of the free circulation of cold air over and between said flanges.

I claim:

1. A lamp embodying an outer cylindrical casing having a closed base and an open top, an outstanding flange at said top, a plurality of open-based cylinders assembled within the upper part of said outer casing, said inner cylinders being of diameters and lengths decreasing in simple proportion, the smallest cylinder being closed at the top, a burner within said outer casing below the inner cylinders, outwardly projecting flanges at the upper ends of said inner cylinders, said flanges being spaced one over another, and the relative disposition and dimensions of the several cylinders and flanges being such as to form within the lamp a space within which a flame will burn undisturbed and unaffected by exterior air currents or other climatic conditions yet producing its own convective currents which have both ingress and egress at the circumference of the top flanges.

2. A lamp comprising an outer cylindrical casing having a closed base and an open top, an outstanding flange at said top, a plurality of open-based cylinders assembled within the upper part of said outer casing, said inner cylinders being of diameters and lengths decreasing in simple proportion, the smallest cylinder being closed at the top, a burner within said outer casing below the inner cylinders, outwardly projecting flanges at the upper ends of said inner cylinders, said flanges being spaced one over another so as to form air inlet and outlet openings at the circumference of the flanges, and the circumferential area of each of said openings being equal to the cross sectional area of that vertical annular passage between two of the cylinders with which said opening communicates.

3. A lamp comprising an outer open-topped cylindrical casing of a height greater than its diameter, a closed base to said casing, a plurality of cylinders concentrically arranged within the upper part of said outer casing, said cylinders being of simple descending proportion, i. e. the diameter of the outermost cylinder being to the second cylinder as the latter is to the third and the lengths or axial dimensions of the inner cylinders being equal to their respective diameters, the several cylinders having outstanding top flanges, said flanges being spaced one over another so as to provide peripheral air-inlet and outlet openings and the total circumfer-

ential area of each such opening being equal to that of the annular passage between the cylinders with which said opening communicates.

5. 4. A lamp comprising an outer cylindrical casing with open top and closed base, a plurality of open-based cylinders assembled concentrically within the upper part of said outer casing, said cylinders being of propor-

tionately decreasing diameters and lengths, 10 a burner within the outer casing below the inner cylinders, outwardly projecting flanges at the top of the outer casing and inner cylinders, said flanges being spaced one over the other and means for enabling the spacing of 15 said flanges to be accurately adjusted.

D. J. G. WATKINS.
